UNITED STATES PATENT OFFICE.

FREDERICK A. WYGANT, OF HORNELL, NEW YORK, ASSIGNOR TO THE A. J. DEER COMPANY, INCORPORATED, OF HORNELL, NEW YORK, A CORPORATION OF NEW YORK.

DESIGN FOR A FRAME FOR SLICING-MACHINES.

53,551.

Specification for Design.

Patented July 8, 1919.

Application filed April 8, 1918. Serial No. 227,384. Term of patent 14 years.

To all whom it may concern:

Be it known that I, FREDERICK A. WYGANT, a citizen of the United States, residing at Hornell, in the county of Steuben and State of New York, have invented a new, original, and ornamental Design for a Frame for Slicing-Machines, of which the following is a specification, reference being had to the accompanying drawing, forming part thereof.

Figure 1 is a perspective view of the rear side of the frame for slicing machines showing my new design. Fig. 2 is a similar view of the same from the front side thereof.

I claim:

The ornamental design for a frame for slicing machines, as shown.

FREDERICK A. WYGANT.
